UNITED STATES PATENT OFFICE

WARREN U. BOTSFORD, OF MOLINE, ILLINOIS, ASSIGNOR TO ROCK ISLAND MFG. CO., OF ROCK ISLAND, ILLINOIS, A CORPORATION OF ILLINOIS

VISE DISPLAY STAND

Application filed March 21, 1932. Serial No. 600,292.

This invention relates to improvements in vise display stands and, more especially, a convenient stand or support adapted to hold a plurality of vises in position for display, examination and manipulation.

Among the features of my invention is the provision of such a stand adapted to support a plurality of vises in a small space, and at the same time permit complete examination and operation of any one of said vises. This is accomplished by supporting the vises by the ends of their beams so that the jaws can be opened and closed without detaching the same from the stand. They are also supported on a rotatable member so that any one at a time can be swung around to the front of the stand for close examination and operation.

Another feature of my invention is the provision of such a stand on which the vises can be readily mounted or dismounted.

Other features and advantages of my invention will appear more fully as I proceed with my specification.

In that form of device embodying the features of my invention shown in the accompanying drawing—

Figure 1 is a view in front elevation, partly in section; and Fig. 2 is a top plan view.

As shown in the drawing, the stand includes a suitable base 10 here shown as circular in form, with upwardly curved ribs or spokes 11 supporting a hub or pedestal 12.

13 indicates a supporting member rotatably mounted on the base. This mounting is accomplished by providing the supporting member with a depending shaft 14 rotatably supported in the hub 12. The supporting

part of the member 13 comprises a square plate provided with radial troughs or channels 13^a defined by the upstanding ribs 13^b. At the inner ends of the troughs 13^a there are provided threaded holes 15 to accommodate the lower ends of vertical machine screws 16

under the heads of which there are provided square plates or washers 17.

The vises are supported in a substantially radially extended horizontal position, as shown in the drawing. A vise 18 is attached by placing the end of its beam 18^a in one of the channels or troughs 13^a and holding the same there by placing the washer or plate 17 on top of the end of the beam and tightening the screw 16.

In Fig. 1, the stand is shown with three vises mounted thereon. It will be seen that when thus mounted, the handle 18^b of the vise 18 may be turned to open and close the jaws 18, thus permitting full inspection and operation of the vise. Since the member 13 is rotatably mounted, the same may be turned to permit any vise carried on the stand to be brought close to the operator for inspection.

While I have shown and described certain embodiments of my invention, it is to be understood that it is capable of many modifications. Changes, therefore, in the construction and arrangement may be made without departing from the spirit and scope of the invention as disclosed in the appended claims, in which it is my intention to claim all novelty inherent in my invention as broadly as permissible, in view of the prior art.

What I regard as new, and desire to secure by Letters Patent, is:

1. A base; a supporting member rotatably mounted on the base, said supporting member including a part with radial troughs having holes in their inner ends; and means for holding the ends of the beams of vises in said troughs, said means including clamping members adapted to engage the upper surfaces of the ends of said beams and co-operating with the holes in the troughs.

2. A base; a supporting member rotatably mounted on the base; and means on the supporting member for holding the ends of the beams of vises, said means including a sup-

port with radial troughs and means for holding the ends of vise beams in said troughs.

3. A base; a supporting member rotatably mounted on the base; and means on the supporting member for holding the ends of the beams of vises and supporting the same in substantially radially extended horizontal position, said means including a support with radial troughs and means for holding the ends of vise beams in said troughs.

In witness whereof, I have hereunto set my hand and seal, this 11 day of March, 1932.

WARREN U. BOTSFORD.
